UNITED STATES PATENT OFFICE.

JOHN McLACHLAN, OF EAST ELMHURST, NEW YORK.

CAM-SHAFT REMOVER.

1,395,587.

Specification of Letters Patent.

Patented Nov. 1, 1921.

Application filed July 24, 1920. Serial No. 206,924.

To all whom it may concern:

Be it known that I, JOHN McLACHLAN, a citizen of the United States, residing at East Elmhurst, in the county of Queens and State 5 of New York, have invented certain Improvements in Cam-Shaft Removers, of which the following is a specification.

This invention relates to devices for removing shafts which are contained within 10 a housing, and more particularly to devices for removing cam-shafts of automobile engines.

When it was desired to remove a cam-shaft from its bearings for the purpose of 15 repairing or replacing said shaft or any of its associated components, it has been customary in the past to resort to laborious and time-consuming operations. Various implements have been employed in such operations, but it has been found that these often cause serious results, such as stripping or otherwise injuring the threads of the cam-shaft, cracking the crank-case and other impairments too numerous to mention. Accordingly, it is one of the principal objects 20 of this invention to provide a device which will remove cam-shafts or the like from their bearings in a manner which will eliminate any degree of damage to the shafts or associated parts. Another object consists in 25 carrying out such operation in a simple and expeditious manner. Other and further objects of the invention will hereinafter appear.

30 In the annexed drawing, Figure 1 is a side elevation of the improved device, shown partly in section, and Fig. 2 is a cross-sectional view taken on the line X—X of Fig. 1, looking in the direction of the arrows.

35 Referring to the drawing, in which like characters represent like parts throughout, 40 5 represents a main body or tubular casing which is preferably composed of steel. Provided on one end of the casing 5 is a handle 45 comprising knurled portions 6, 6, and these portions, if desired, may be separated by grooves as indicated. Formed at the opposite end of the casing is a chamber-portion 7 which is of sufficient length and diameter 50 to pass freely over and inclose the end of the largest shaft or shaft bushing which it is likely to engage. The outer circular end 8 of the chamber-portion is cut on a straight vertical line so as to bear flush against the 55 surface of the crank-case with an equal pres-

sure throughout, as will later appear. Connected with the chamber-portion 7, and extending laterally therefrom and longitudinally of the casing is a bored-out portion 9 having a smooth surface, which provides a guideway in which a threaded member or pull-screw 10 may reciprocate. The member 10 is of smaller diameter than the guideway 9, and accordingly there is a clearance 60 therebetween. Integral with the member 10, and formed at one end thereof, is a head 11 which is of slightly larger diameter than the member 10 and slidably engages the guideway 9 and is adapted to reciprocate with the member 10 in said guideway, thereby centering and guiding the member 10 therein. The head 11 is provided with a bored-out portion 12 having internal threads formed therein for engaging the end of a cam-shaft. At the extremity of the threaded member 10 70 opposite the head 11 is a slot 13 which is for the purpose of permitting the use of a screw-driver, when it is necessary to screw the threaded portion 12 on the end of a cam-shaft. At 14 is indicated the threaded end of a cam-shaft 15, shown as journaled 75 in a bearing 16 and provided with the usual bushing 17, said bearing being mounted within an engine-casing 18. A nut 19 is threaded on the member 10 after the head 80 11 has engaged the end of the cam-shaft and serves to withdraw the member 10 from the guideway 9, as will later appear.

In the operation of the improved device, 85 the chamber-portion 7 thereof is fitted over the bushing on the cam-shaft so that the circular end 8 lies flush with the casing 18. The device is held by the knurled portions 6 against said casing, and the pull-screw or threaded member 10 is pushed forwardly 90 in the guideway 9 until the threaded portion of chamber 12 engages the threaded portion on the end of the cam-shaft 15. If any difficulty is experienced in engaging said threaded portions, a screw-driver may be 95 applied to slot 13 and pressure transmitted thereby to the pull-screw 10. When said members are engaged the nut 19 is placed on the end of the pull-screw and threaded thereon until it contacts with the end of the 100 casing 5. At such time, the continued travel of the nut on the threaded member will result in increased pressure of the circular portion 8 against the casing 18 causing the recession of the pull-screw from the guide- 105 110

way and the removal of the cam-shaft from its bearings, after which it may be readily taken from the casing by hand.

From the foregoing it is thought that the 5 construction, operation and many advantages of the herein described invention will be apparent to those skilled in the art without further description, and it will be understood that various changes in the size, shape, 10 proportion and minor details of construction, may be resorted to without departing from the spirit or sacrificing any of the advantages of the invention.

What is claimed is:

- 15 1. A device for removing cam-shafts, comprising a casing, a chamber portion at one end thereof, a guideway connected with the chamber portion and extending laterally therefrom, a threaded member movable in said guideway, a head member integral with the threaded member for guiding and centering said member in said guideway, and means for reciprocating said threaded member and head member in the guideway.
- 20 2. A device for removing cam-shafts, comprising a casing, a chamber portion at one end thereof, a guideway connected with the chamber portion and extending laterally therefrom, a threaded member movable in said guideway, a head member integral with the threaded member for guiding and centering said member in said guideway, a slot provided in the end of the threaded member for moving said member in the guideway in
- 25
- 30

one direction, and a member associated with 35 the threaded member for moving said member in the opposite direction.

3. A device for removing cam-shafts, comprising a casing, a chamber portion at one end thereof, a guideway connected with 40 the chamber portion and extending laterally therefrom, a threaded member movable in said guideway, a head member integral with the threaded member for guiding and centering said member in said guideway, a slot 45 provided in the end of the threaded member for moving said member in the guideway in one direction, and a nut on said threaded member for moving said member in the opposite direction. 50

4. A device for removing cam-shafts comprising a casing, a chamber portion at one end thereof, a guideway connected with the chamber portion and extending laterally therefrom, a pull-screw movable in said 55 guideway, a head member integral with the pull-screw for guiding and centering the pull-screw in said guideway, means in said head member for engaging a cam-shaft, a slot on the pull-screw for moving said means 60 into engagement with the shaft, and a nut threaded on the pull-screw for withdrawing said screw from the guideway and said shaft from its bearings.

In testimony whereof, I have signed my 65 name to this specification this 24th day of July, 1920.

JOHN McLACHLAN.
